UNITED STATES PATENT OFFICE.

PETER BROMAN, OF CHICAGO, ILLINOIS, ASSIGNOR TO BROWN SAFETY LADDER MFG. CO., OF CHICAGO, ILLINOIS, A CORPORATION OF ILLINOIS.

LADDER-MAKING MACHINE.

1,426,255.

Specification of Letters Patent. Patented Aug. 15, 1922.

Application filed October 31, 1919. Serial No. 334,834.

To all whom it may concern:

Be it known that I, PETER BROMAN; a citizen of the United States, residing at Chicago, in the county of Cook and State of Illinois, have invented a new and useful Improvement in Ladder-Making Machines, of which the following is a specification.

This invention relates to machines for and processes of making ladders of the type 10 shown and described in the patent to Charles J. Brown, No. 1,246,709, granted November 13, 1917.

This ladder has straight wood sides and rungs made of angle iron with the cords 15 cut back in such a way as to form tynes which can be forced through the sides and clinched so that a firm attachment between the rung and side is obtained.

Heretofore the method of making up this 20 ladder has been to pound in the rungs one at a time by hand. The labor necessary to do this is enormous and costly and the ladder when finished is often out of true.

It is an object of this invention to provide a method of and machine for making 25 a ladder of several rungs at a single actuation of the machine.

This and other objects which will appear 30 from the following specification are accomplished by my invention, an embodiment of which is illustrated in the accompanying drawings in which,

Figure 1 is a partial plan view showing 35 the drive and the first press with a section of a ladder in place;

Fig. 2 is a partial rear side elevation of 40 the same but showing two presses; and

Fig. 3 is a section on the line 3—3 of Fig. 1.

Fig. 4 is an enlarged cross sectional view of a ladder before being assembled.

I have illustrated as an embodiment of 45 my invention, a machine having a frame made up of upper horizontal rear and front angles 10 and 11 respectively, connected at the ends by end angles 12, one end only being shown, and supported by rear support angles 13, 14 and 15, and front support angles 13^a, 14^a and 15^a which are adapted to rest on 50 the floor.

A countershaft 16 is journaled in bearings carried on cross members of the main frame and has journaled thereon a flywheel pulley 17 which is operatively connected by a 55 clutch, the mechanism of which will later

be explained and which has an element 18 secured to the shaft 16 and to the pinion 19. This is meshed with the large gear wheel 20 which is keyed on the main shaft 21 which runs the entire length of the 60 presses and is journaled in the bearings on the main frame.

The presses which will now be described are placed so as to fall at the points at which rungs are to be placed in the ladder. 65 If desired these presses could be made adjustable along the frame so as to accommodate ladders of different rung spacing. I have preferred, however, to show them solidly held. These presses are all alike and 70 each is driven by a cam 22 keyed on the shaft 21 and a cam roller 23 rotatably mounted on a lever arm 24 fulcrumed on a pin 25 on the main frame, the opposite end of the lever carrying a pin 26 on which 75 is mounted a link 27. This link is carried at its forward end by a pin 28 in the block 29. This block is slidably mounted on a guide 30 forming part of the main frame 80 and bolted thereto.

It will be apparent from the foregoing that as the shaft 21 revolves, the block 29 will be slid forward and back along the guide 30.

The pin 28 also carries an arm 31 hav- 85 ing a curved portion 31^a and a slightly inclined portion 31^b adapted to contact the roller 32 which is rotatable on the pin 33 and carried on the bracket 34, the latter being secured to the main frame angle 10. 90 The pin 28 also has hingedly mounted thereon a bifurcated clamping arm 35 which has an upstanding ear 36. A bolt 37 is placed through this ear and through the web of the arm 31 and carries an adjusting nut 95 37^a, thereby serving to form a limit to which the arms 31 and 35 can be separated while a compression spring 38 acts to keep them separated.

Each sliding block 29 has secured on its 100 under surface a lug 29^a hingedly carrying one end 39 of an adjustable link 40 by means of a pin 41. The opposite end 42 of this link is connected by means of a pin 43 with a rocker arm 44 which is hingedly 105 pinned at 45 to the stationary block 46, which is secured to the main frame, and adjustably positioned by screws 46^a. The pin 45 also has hingedly mounted thereon, a clamping arm 47 which has at its outer end a lug 110

having a hole through which passes a bolt 48. The opposite end of this bolt passes through a hole in the upper end 44^a of the rocker arm 44, and a nut 49 permits of adjustment thereon, while a spring 50 tends to keep the members 44^a and 47 separated as far as the bolt 48 will permit.

The lever arm 24 carries a follower 51 which is hingedly mounted on the pin 23^a, 10 the opposite bent end 51^a of the follower being pressed against the hub 22^a of the cam 22 by means of a spring 52. The bent end of the follower is adapted to engage the pin 22^b on the cam 22 so as to cause the lever arm 15 24 to be drawn back to the starting position following each pressing operation. As shown in Fig. 3 the machine is in the position when the maximum pressure is exerted on the ladder. As the cam 22 is 20 turned the lever arm 24 together with the clamping elements will remain in the position shown in Fig. 3 until the pin 22^b strikes the bent end 51^a of the follower 51. As the cam turns further the follower will 25 be drawn with it retracting the lever arm 24 and releasing the press. The complete operation of this press will later be explained.

The flywheel 17 has a pin 52^a securely set 30 in its hub and which is adapted to engage the pin 53 in the clutch element 18 to drive the clutch and the gear 19. This pin is slideable in a longitudinal hole in the clutch member and carries a pin 53^a which projects 35 laterally through a slot in the periphery of the clutch member. A spring 54 presses the pin 53 toward the flywheel.

A round pin 55 carried by the main frame has a square block 56 rotatable thereon which 40 is hingedly mounted in a tapering hole in the rocker arm 57 so that the rocker arm is free to rotate and to have a limited movement in a plane at right angles to the plane in which it normally rotates. A spring 58 45 is attached to the rocker arm and to the frame, and lies diagonally so that it pulls downwardly and toward the flywheel at the same time. A stop member is provided having a straight vertical face 59 and a shoulder 50 60. A link 61 and a foot pedal 62 are provided to raise the rocker arm from its normal position wherein the face 57^a of the rocker arm 57 holds the pin 53^a and hence holds the pin 53 in a retracted position, so 55 that the clutch is disengaged. When, however, it is desired to cause the clutch to engage to drive the machine, the operator pushes down on the foot pedal raising the rocker arm 57 until it reaches the shoulder 60 65 when the spring 58 draws it toward the flywheel as shown in full lines in Fig. 1, and allowing the pin 53 to be forced out by the spring into the path of the pin 52^a. The flywheel is being continuously driven prefer- 65 ably by a belt.

In order to automatically disengage the clutch a sloping lug 63 is placed on the gear 20 in the path of the outer end 57^b of the rocker arm. This merely forces the rocker arm back so that the spring can act to return it to its normal position as shown in dotted lines in Fig. 1. The normal position for disengagement of course is when the block 29 is near the extreme outward end of its throw. 75

The operation of my ladder making machine is as follows: The presses being in the normally open position with the blocks 29 drawn back the full amount, the wood side bars A, A' of the ladder are placed in position with their ends abutting a stop at one end of the machine. The rungs B are placed in the holders 64 which are bolted to the guides 30 but are so spaced that they provide the necessary end play. The latter parts 80 are then loosely arranged in the position shown in Fig. 4.

At this time the curved portion 31^a of the arm 31 is resting on the roller 32 and the clamping arms 35 and 47 are raised so as to 90 permit of a ready insertion of the side bars. The operator then steps on the foot pedal causing the clutch to engage and drive the shaft 21 through the cams 22 to force the block 29 toward the ladder elements. As it 95 moves the arm 31^b strikes the roller 32 and raises forcing the clamping arm 35 down on the ladder side bar A. The point at which this occurs may be adjusted by means of the bolt 37 and nut 37^a, and the force applied is 100 varied by varying the compression of the spring 38.

The link 40 causes the clamping arm 47 to act in a similar manner on the ladder side bar A'. The rungs of this ladder preferably 105 consist of angle iron having a recessed portion at each end thereby forming a flat chisel portion B' and a nail like point B^a at each end with an abutment B^b which acts as a stop. As the block 29 advances these prongs 110 are forced through the side bars and are clinched by the hardened steel plates 29^a as shown in Fig. 3 where the press has reached the limit of its throw. As the shaft 21 continues to revolve, the block 29 is retracted, 115 the clamping arm 47 releasing before the clamping arm 35, so that the assembled ladder is drawn back somewhat from the clamp 47 so as to make it easier to remove.

It will be understood, however, that this 120 machine can with slight changes be adapted to the manufacture of various kinds of ladders where the rungs are forced into the side bars, which may be made of metal as well as of wood.

The screws 46^a may be set for different widths of ladders. The link 40 must then be adjusted to correspond.

While I have shown and described but a single embodiment of my invention, it is to 130

be understood that it is capable of many modifications. Changes therefore in the construction and arrangement may be made without departing from the spirit and scope 5 of the invention as disclosed in the appended claims.

What I claim as new and desire to secure by Letters Patent is:

1. A machine for pressing metal rungs 10 into side bars including relatively movable plates adapted to press said side bars, means for relatively positioning the rungs and side bars, adjustably connected means to clamp the tops of said side bars, and means for 15 forcing said plates toward each other, said latter means including a plurality of slideable blocks, a cam for moving each of said blocks and a cam shaft for moving said cams.
2. A machine for pressing metal rungs 20 into side bars comprising relatively movable plates adapted to press said side bars, means for relatively positioning the rungs and side bars, and means for forcing said plates 25 toward each other, said latter means including a plurality of slideable blocks, a cam for moving each of said blocks and a cam shaft for moving said cams, a counter shaft and clutch associated therewith for driving the cam shaft one revolution for each actuation 30 of said clutch, and interconnected clamping

means adapted to engage the tops of said side bars upon the operation of the cam mechanism.

3. A machine for making ladders, comprising a frame, a series of presses thereon and means for actuating said presses simultaneously to force the ladder rungs into the side bars, means for actuating said presses and clamps associated therewith for holding 40 the side bars in fixed position, one of said clamps being releasable before the other so that the ladder will be withdrawn from the other clamp as the press is released.

4. A machine for making ladders, a frame, 45 a series of presses thereon and means for actuating said presses simultaneously to force the ladder rungs into the side bars, movable and stationary clamps associated therewith for holding the side bars in fixed 50 position, the stationary clamps being releasable before the movable clamps so that the ladder will be withdrawn from the stationary clamps as the press is released.

5. A machine for pressing steel ladder 55 rungs into ladder side rails comprising a frame, a series of presses thereon, means for actuating said presses simultaneously to force the ladder rungs into the side rails and plates for clinching the ends of said rungs in the side rails.

PETER BROMAN.
